Inventor:

UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 14,548, dated January 15, 1884.

Application filed November 19, 1883. Term of patent 3½ years.

To all whom it may concern:

Be it known that I, CATHERINE O'HARA, of the city, county, and State of New York, have invented and produced a new and original Design for a Pattern of a Girl's Costume, (numbered 8,970;) and I do hereby declare that the engraved prints accompanying this specification convey to any one accustomed to using paper patterns a clear understanding of how a garment made up by the pattern will appear.

This design shows a deep yoke-section at the back and another at each side of the center of the front, each crossed at the bottom by a plaited ornament; a lower portion that ex-

hibits three box-plaits at the back and three in the front, the middle one of the front extending to the neck; curved ornamental sections low down at the sides; coat-sleeves, and a standing collar.

What I claim as my invention, and desire to secure by Letters Patent, is—

The design for a girl's costume, as shown in the engraved prints accompanying this specification.

CATHERINE O'HARA.
